(57) **CLAIM**

The ornamental design for a screening device for sleep disordered breathing, as shown and described.

DESCRIPTION

FIG. 1 is a front perspective view of a screening device for sleep disordered breathing according to our design;

FIG. 2 is a front view thereof;

FIG. 3 is a rear view thereof;

FIG. 4 is a top view thereof;

FIG. 5 is a right side view thereof; and,

FIG. 6 is a left side view thereof.

Where included, broken lines represent environmental structure and do not form a part of the claimed design.
